HAIR CLIPPER

Fred T. Hotz, Stephen Sadlon, and Ellis M. Brown,
Racine, Wis., assignors to John Oster Manufacturing Company, Racine, Wis., a corporation of Wisconsin

Application March 11, 1949, Serial No. 80,788

1 Claim. (Cl. 30—132)

1

This invention relates to hair clippers and refers more particularly to clippers of the electric motor driven type.

One such type of clipper which has obtained wide popularity is shown and described in Patent No. 2,182,597 issued to John Oster, December 5, 1939.

The clipper of this invention is similar to that of the aforementioned patent in that it likewise has an elongated body provided with a hollow handle portion serving to house the electric motor of the clipper; while the cutting blade assembly is mounted on the outer extremity of a forward extension on the handle. The movable blade of the cutting head assembly is likewise driven by the electric motor through transmission means located in a well or cavity in the handle extension opening to the top of the clipper and normally covered by a plate which extends forwardly to a point closely adjacent to the cutting edge 20 of the cutting blade assembly.

Heretofore, it was possible for hair clippings to enter into the working mechanism and the blades of the cutting assembly, and such clippings frequently interfered with the proper operation of the clipper.

Another annoying objection is that hair piles up on cutting edges of the blades and conceals the same from the view of the barber or other operator of the clipper.

With these objections in mind, this invention has as its main object the provision of means for positively precluding hair clippings from entering the working mechanism of the clipper and for precluding accumulation of the clippings on the cutting edges of the clipper blades, thereby assuring proper operation of the blades.

More specifically this invention has as its object the provision of a hair clipper of the character described wherein an impeller inside the hollow handle driven by the electric motor of the clipper is utilized to blow hair clippings from the cutting edge of the cutting blade assembly during use of the clipper.

With this objective in mind, it is another object of this invention to provide a clipper of the character described with cover means for closing the transmission well in the handle extension of the clipper, and which cover means has an air passageway formed therein for leading air 50 set into motion by the impeller of the clipper from the motor housing forwardly along the top of the handle extension directly to the cutting edge of the cutting blade assembly so as to enable hair clippings accumulating on the cutting edge to 55 be blown from the clipper during use thereof.

2

More specifically it is an object of this invention to provide novel closure means for the mouth of the well in the handle extension of an electric clipper of the character described, which closure means comprises cooperating superimposed cover plates forming a channel or passage therebetween for leading air set into motion by the impeller of the clipper forwardly along the handle extension and onto the cutting edge of the cutting blades to keep the same free of hair clippings.

With the above and other objects in view, which will appear as the description proceeds, this invention resides in the novel construction, 15 combination and arrangement of parts substantially as hereinafter described and more particularly defined by the appended claim, it being understood that such changes in the precise embodiment of the herein disclosed invention may be made as come within the scope of the claim.

The accompanying drawing illustrates one complete example of the physical embodiment of the invention constructed according to the best mode so far devised for the practical application of the 25 principles thereof, and in which:

Figure 1 is a side view of the front end portion of an electric clipper, having portions shown in elevation and portions in section to better illustrate the application of this invention thereto;

Figure 2 is a plan view of that portion of the clipper shown in Figure 1, likewise having parts broken away and shown in section; and

Figure 3 is a cross sectional view through Figure 2 taken along the plane of the line 3—3.

Referring now more particularly to the accompanying drawing in which like numerals indicate like parts, the numeral 4 generally designates the clipper of this invention. The clipper has an elongated body 5 only the front end portion of which is shown, and the body comprises a tubular handle portion 6 which serves as a housing for an electric motor 7, and a forward extension 8 on the front end of the body having a well 9 opening to the top 10 of the body and in which transmission means 11 is mounted.

The cutting head 12 of the clipper may be attached to the outer extremity of the handle extension in any desired manner, but in the present case, there is a readily detachable connection, generally indicated at 13, between the head and the extension. This connection is merely illustrative, and is shown and described in greater detail in the aforementioned Patent No. 2,182,597. It is sufficient to note that the cutting head comprises a stationary cutting blade 14 and a movable cutting blade 15, and that the cooperating

blades are mounted on the outer extremity of the handle extension with their cutting edges 16 disposed adjacent to the top of the clipper body and slightly above the mouth of the well 9 in the handle extension. It should be observed also that the movable cutting blade 15 is held against the back side of the stationary blade 14 under a degree of spring tension by means of a spring element 17 having its inner end fixed to the stationary blade as at 18 and having a V-shaped outer extremity 19 received in a substantially V-shaped notch 19' in the back side of the movable cutting blade. The notch 19' extends entirely across the back of the movable blade a slight distance inwardly of its cutting teeth. Also, the back side of the movable cutting blade is spaced from but faces the outer extremity of the handle extension 8.

Inasmuch as the forwardly indented or V-shaped outer extremity of the spring element 17 extends uninterruptedly and substantially entirely across the width of the movable cutting blade, as shown in greater detail in the aforementioned patent of John Oster, it will be clear that the movable blade is constrained to reciprocatory motion crosswise of the outer extremity of the handle extension 8.

Reciprocation is imparted to the movable blade 15 by means of an oscillatory lever 20 pivotally carried by the handle extension and having an arm 21 projecting forwardly from the outer extremity of the extension into a notch, not shown, in the movable cutting blade to drive the same in a conventional manner. A rearwardly projecting arm 22 of the lever connects with the transmission means 11 inside the well 9 in the handle extension, and the transmission means is, in turn, connected with the shaft 23 of the electric motor 7.

The motor housing and the transmission well are separated from one another by a transverse partition member 25 adjacent to the junction between the handle portion of the clipper body and the forward extension 8. This partition member provides one of the bearings for the shaft 23 of the electric motor, and has a hole 26 therethrough adjacent to the mouth of the well 9 in the handle extension and through which air set into motion by an impeller 27 driven by the electric motor 7 is adapted to be discharged from the hollow handle portion and directed forwardly toward the cutting edge of the cutting head.

In the past, the impeller 27 has had only the single function of cooling the electric motor 7, by drawing air into the interior of the hollow handle through ports at the end of the handle remote from the forward extension 8 thereon, and discharging such air through side vents 29 in the clipper body adjacent to the inner end of the handle extension. According to the present invention, however, part of the air set into motion by the impeller is discharged through the hole 26 in the partition member 25 to flow forwardly toward the cutting edge of the cutting head.

The air discharging through the hole 26 is led forwardly along the top of the handle extension 8 through a passageway 30, the inner end of which connects with the hole 26, and the forward or outer end of which opens directly to the rear surface of the movable cutting blade adjacent to the cutting edge 16 thereof. Hence, a continuous stream of air is discharged onto the toothed edge of the movable cutting blade to blow hair

clippings therefrom during operation of the clipper.

The passageway 30 is preferably formed as part of a novel closure 31 for the mouth of the well 9 in the handle extension, and as seen best in Figures 1 and 3, the closure 31 comprises a relatively flat bottom plate 32 and a top plate 33. The rear or inner ends of the plates abut the outer face of the partition member 25, and the outer plate 33 has an outwardly pressed central portion 34 extending longitudinally of the closure from the front to the rear extremities thereof. A plurality of screws 35 passing through opposite sides of the closure and threading into the opposite sides of the handle extension securely hold the closure in place on the top of the handle extension.

Attention is directed to the fact that at the front end of the closure 31, both the upper and lower cover plates extend forwardly beyond the outer extremity of the handle extension and over the space between said forward extremity of the extension and the adjacent portion of the cutting head assembly. This disposes the outer extremities of the upper and lower plates directly adjacent to the back of the movable cutting blade, as stated, and it will be seen from a consideration of Figure 2 that the forward extremities of both plates extend for substantially the full width of the movable cutter and the V-shaped extremity of the spring element 17 by which the cutter is constrained to reciprocatory movement.

As best shown in Figure 1 the free outer extremity of the lower plate 31 is curled downwardly and rearwardly as at 36 and is engaged under a degree of spring tension with the V-shaped extremity of the spring element 17 so as to provide a seal extending entirely across the front of the clipper by which hair clippings are prevented from entering the space behind the cutting head during operation of the clipper. Hence, since the forward extremity of the upper plate 33 is spaced slightly from the adjacent portion of the cutting head, the air discharging onto the back of the cutting head at the cutting edge thereof will flow upwardly and outwardly over the cutting edge of the head and largely prevent hair clippings from accumulating on the clipper head.

Referring to Figure 2, it will be seen that the hole 26 in the partition member 25 of the body is in the nature of a slot having its long dimension crosswise of the axis of the body, and that the passageway 30 formed between the inner and outer covers of the closure 31 has a width which substantially corresponds to the width of the hole 26 at the inner end of the passageway, while the outer end of the passageway diverges as at 38 toward the cutting edge of the clipper head until it achieves substantially the full width of the movable cutting blade at the outer end of the passageway.

From the foregoing description taken in connection with the accompanying drawing, it will be readily apparent to those skilled in the art that this invention provides an electric hair clipper wherein hair clippings are prevented from accumulating at the cutting edge of the cutting blade assembly; and wherein entry of clippings into the space behind the cutting head, where they might interfere with proper operation of the blades is positively precluded.

What we claim as our invention is:

In an electric clipper of the character described: an elongated body having a handle por-

tion serving to house the electric motor of the clipper, and a forward extension on one end of the handle portion having a well opening to the top side of the body to house the transmission means of the clipper; an impeller in the handle portion driven by the motor to effect cooling thereof; said body having an air discharge port therein near the inner end of the handle extension and adjacent to the mouth of said well to enable air in the handle portion of the body to be blown forwardly therefrom; a cutting head including cooperating stationary and movable cutting blades mounted on the outer extremity of said forward extension with their cutting edges at the top of the body and extending crosswise of the handle extension in spaced relationship to the outer extremity thereof; a spring element overlying the back of the movable blade and pressing the same against the stationary blade, said spring having a tongue and groove connection with the movable cutting blade near the cutting edge thereof by which the movable blade is constrained to reciprocatory motion crosswise of the outer extremity of the handle extension; and closure means fixed to the handle extension in a position covering the top thereof so as to close the mouth of the well in the extension, said closure means including upper and lower cover plates projecting forwardly beyond the outer extremity of the handle extension and across said space toward the cutting edge of the cutting head,

5

the outer extremity of the lower plate having a downwardly and rearwardly curled lip engaging said spring element under a degree of spring tension substantially at the connection of the spring element with the movable cutting blade to provide an effective seal precluding the entrance of hair clippings into said space between the cutting head and the outer extremity of the handle extension and the upper plate having an upwardly channeled central portion cooperating with the lower plate to define an air passageway leading from said air discharge port to the cutting edge of the cutting head so that hair clippings are blown therefrom during use of the clipper.
